INVENTOR

R. W. Jones.

UNITED STATES PATENT OFFICE.

RICHARD W. JONES, OF SYRACUSE, NEW YORK.

GAG-RUNNER.

SPECIFICATION forming part of Letters Patent No. 225,391, dated March 9, 1880.

Application filed February 9, 1880.

To all whom it may concern:

Be it known that I, RICHARD W. JONES, a citizen of the United States, residing at Syracuse, in the county of Onondaga and State of New York, have invented a certain new and useful Improvement in Gag-Runners for Horses' Bridles; and I do hereby declare that the following is a full, clear, and exact description of the invention, reference being had to the accompanying drawings, making a part of this specification, in which—

Figure 1 is a perspective view of my improved gag-runner. Fig. 2 is a side view.

Heretofore the construction of this class of articles has been somewhat troublesome and expensive, as they have been made of cast metal; and as the loop for the rein and the one by which it is secured to a bridle or other part of a harness are at right angles to each other, it was necessary either to cast them with a core, or else cast both loops in the same plane, then submit the cast article to an annealing process, and afterward bend the one loop at right angles to the other. My invention obviates these difficulties, is easier and cheaper of construction, and neater and more durable in use.

In the formation of my link I take a piece of round or oval wire, double it in the middle

to form the loop A for the rein, then twist the two ends together to form the shank B, giving it one or more turns, as may be desired, and then bend the free ends, first outwardly from the shank, and then inwardly, until the two ends are adjacent, to form the loop C, by means of which loop the device is attached to the harness.

The only opening is at the top of the loop, where it is entirely concealed after its attachment to the strap, and has the appearance of continuity.

The runner may be tinned or plated, as may be desired, and may be constructed by hand or by suitable machinery.

It will be obvious that a gag-runner made as above described, of wrought metal, will be superior to the cast ones now chiefly used.

Having thus fully described my invention, what I claim is—

A gag-runner for harness made of a single piece of wire, and having the closed loop for the rein, the twisted shank, and the loop C, all constructed and operating substantially as shown and described.

RICHARD W. JONES.
